HOOK FOR USE ON TOILET TANKS

Samuel L. Johnson, 319 Dixie Way N., South Bend, Ind.

Filed Jan. 9, 1958, Ser. No. 49,181

Term of patent 3½ years

(Cl. D17—12)

FIG. 1

FIG. 3

FIG. 2

FIG. 4

FIGURE 1 is a perspective view of a hook for use on toilet tanks showing my new design;

FIGURE 2 is a front elevational view;

FIGURE 3 is a side elevational view; and

FIGURE 4 is a rear elevational view thereof.

The broken line showing is for illustrative purposes only.

I claim:

The ornamental design for a hook for use on toilet tanks, substantially as shown and described.
